(57) **CLAIM**

The ornamental design for a gripping pencil topper and sharpener, as shown and described.

DESCRIPTION

FIG. 1 is a perspective top and front view of the gripping pencil topper and sharpener.

FIG. 2 is a front view of the gripping pencil topper and sharpener.

FIG. 3 is a back view of the gripping pencil topper and sharpener; and,

FIG. 4 is a top view of the gripping pencil topper and sharpener.

The stippling on the grip represents a surface texture and is part of the claimed design.

The gripping pencil topper and sharpener is intended to be used to fit on and around the head of a pencil so that a user may both sharpen the pencil without removing the gripping pencil topper and sharpener and more easily grip the pencil while writing with the pencil. As a pencil is sharpened by the gripping pencil topper and sharpener, only the graphite of the pencil protrudes through the top of the gripping pencil topper and sharpener.
